ARMCHAIR

John S. Burdick, North Muskegon, Mich., assignor to The Shaw-Walker Company, Muskegon, Mich., a corporation of Michigan

Application August 2, 1950, Serial No. 11,543

Term of patent 14 years

(Cl. D15—1)

To all whom it may concern:

Be it known that I, John S. Burdick, a citizen of the United States, residing at North Muskegon, in the county of Muskegon, State of Michigan, have invented a new, original, and ornamental Design for an Armchair, of which the following is a specification, reference being made to the accompanying drawing, forming part thereof, wherein:

Figure 1 is a front view of an armchair, showing my new design;

Figure 2 is a side view of an armchair, showing my new design; and

Figure 3 is a three-quarter perspective view of an armchair, showing my new design.

The design is characterized by the rearward flare of the back splats and back cross bar, the flared connection of the chair arms to the opposite sides of the seat frame and the contrasting appearance shown by means of shading in the full lines portion of the drawing.

I claim:

The ornamental design for an armchair, as shown and described.

JOHN S. BURDICK.
